UNITED STATES PATENT OFFICE.

JOHN FRANK HARRISON, JR., OF MEXICO, MISSOURI, ASSIGNOR OF ONE-HALF TO
JAMES M. HARRISON, OF MADISON, MISSOURI.

ENSILAGE-COMPRESSOR.

1,264,645.

Specification of Letters Patent. Patented Apr. 30, 1918.

Application filed October 9, 1916. Serial No. 124,579.

To all whom it may concern:

Be it known that I, JOHN F. HARRISON, Jr., a citizen of the United States, residing at Mexico, in the county of Audrain, State 5 of Missouri, have invented certain new and useful Improvements in Ensilage-Compressors; and I do hereby declare the following to be a full, clear, and exact description of the invention, such as will enable others 10 skilled in the art to which it appertains to make and use the same.

This invention relates to ensilage compressors or packers, and has particular reference to a mechanism for packing down ensilage 15 in silos.

The invention has for its object to provide an improved mechanism for evenly packing the material which is filled into a silo around the inner wall of the silo as well as in the 20 center, a particular mechanism being provided for controlling the packing element.

With the above objects in view and such other objects as will hereinafter appear my invention will now be fully set forth and 25 described, reference being had to the accompanying drawings.

In the drawings:

Figure 1 is a vertical section through a silo showing my invention in operative form, 30 Fig. 2 is a side elevation of the machine for raising the weight,

Fig. 3 is an enlarged detail view of a traveler or carriage employed as a part of the invention,

Fig. 4 is an enlarged detail view of the weight adjusting mechanism, and

Fig. 5 is a further detail view.

Referring more particularly to the drawings 1 represents the wall of a silo which is 40 surmounted by a number of beams 2, the latter meeting in an apex over the middle of the silo. At their apex, the beams 2 are provided with a bearing in which is vertically 45 slideable a hanger 3 whose lower end has swiveled thereto a pulley block 4. The upper end of the hanger is provided with a coil 50 spring 5, the upper end of the hanger being threaded to receive a head for the spring and the opposite end of the latter being 55 rested against the bearing. The upper end of the beams 2 are clamped by means of the bolts 6, and brackets 7 carried by the lower 60 ends of the beams 2 clamp the beam structure to the upper edge of the silo wall. One

of the brackets 7 carries a standard 8 upon 55 which is mounted the yoke 9 in which a pair of guide pulleys 10 revolve. The pulleys 10 and the block 4 provide a means for guiding a cable 11 into the silo. The inner end of the cable 12 is provided with a block 12 carrying the pulley 13 which coöperates with a pulley 14 carried by a weight or tamper 15. The tamper 15 is suspended from the cable 11 by means of an adjusting cable 16 which is passed a suitable number of times over the 60 pulleys 13 and 14, the latter being doubled or tripled as the particular construction requires. A latch 17 upon the block 12 provides a means for locking the end of the cable 16 at any desired position of adjustment. 65 Surrounding the inner face of the wall 1 near its upper edge is an endless trackway 18 which consists of a tubular structure, as an iron pipe and is carried upon the L-shaped brackets 19 in such relation that substantially 70 the whole peripheral surface of the tubular trackway is free to provide a continuous bearing for the travel of a carriage 20. The carriage 20 consists of a substantially split ring structure which carries 75 at its ends, the conical rollers 21 which bear upon the under surface of the tubular trackway 18 and the roller 22 which rides upon the top of the trackway. Upon its inner side, the carriage 20 is provided with an off-set 80 in which is mounted the multiple pulley 23. The multiple pulley 23 coöperates with a corresponding pulley 24 in carrying a cable 85 25. The pulley 24 is carried by a block 26 through which the cable 11 passes and is 90 therein guided by means of a roller or pulley 27. The carriage 20, the block 26 and the cable 25 provide a means for varying the distance between the tamper 15 and the wall 95 of the silo, the operator standing within the silo and drawing up the cable 25 until the approach of the block 26 to the carriage 20 has positioned the tamper.

The outer end of the cable extends to the ground or to the other suitable point where 100 the actuating mechanism is located. The latter consists of a base 28 upon which is rotatably mounted a comparatively large disk 29. Said disk is connected by means of a belt 30 to a suitable power source, preferably, the ensilage cutter driving mechanism. Upon one face of the disk 29 is provided the roller 31 which is positioned to strike against

and carry for a certain distance the trip lever 32, to which the outer end of the cable 11 is secured as in the coupling 33 carried by the trip lever 32. The outer end of the trip lever 32 is pivoted in a standard 34, and its upward movement is limited by a stop 35 which consists of a vertical standard having its upward end overturned to impress the trip lever 32, so that the latter is pulled upwardly by the tamping weight of the roller 31 as passed out of engagement with the trip lever, the latter will not fly wildly around its fulcrum.

The operation of the mechanism is apparent from the foregoing description, but it should be noted that the mechanism is so mounted that the tamper may be easily swung from one locality to another within the silo with little effort, the operator pulling up or letting out on the cable 25 in order to position the tamper 15 radially, and shoving the carriage 20 around the trackway 18 in order to position the weight circumferentially. In this way without difficulty, the weight may be brought to operative position over any point within the silo. By means of the cable 16, the immediate adjustments which are required to meet the rise of the ensilage in the silo may be met. When further vertical compensation is necessary the outer end of the cable 11 is adjusted in the coupling 33 upon the trip lever 32. The coil spring support for the hanger 3 provides a means for taking up the jar and vibrations caused by the rise and fall of the tamper.

What I claim is:—

1. An ensilage packing mechanism, comprising in combination, a tamper, flexible means for suspending said tamper from a central point, means for actuating the suspended means to operate the tamper, a carriage movable around the central point, and a connection between said carriage and the tamper suspending means for bending the latter to vary the distance of the tamper from the carriage.

2. An ensilage packing mechanism, comprising in combination, a tamper, means for suspending the tamper centrally in a silo, a trackway around the inside of the silo, a carriage operative over said trackway, a pulley surrounding said tamper suspending means and means connecting said pulley to the carriage for varying the distance between the tamper and the side of the silo.

3. An ensilage packing mechanism, comprising in combination, a tamper, a means for resiliently suspending the tamper centrally from the top of a silo, a track-way arranged around the upper portion of the silo, a carriage operative over said track-way and a flexible connection operative on the tamper suspending means, for drawing the tamper toward the side of the silo, and means for raising and releasing the tamper.

In testimony whereof, I affix my signature, in the presence of two witnesses.

JOHN FRANK HARRISON, JR.
